UNITED STATES PATENT OFFICE.

CHARLES PUDDEFOOT, OF DETROIT, MICHIGAN, ASSIGNOR TO BRISCOE MANUFACTURING COMPANY, OF DETROIT, MICHIGAN, A CORPORATION OF MICHIGAN.

DESIGN FOR A STOVE.

SPECIFICATION forming part of Design No. 36,090, dated September 30, 1902.

Application filed August 15, 1902. Serial No. 119,824. Term of patent 7 years.

To all whom it may concern:

Be it known that I, CHARLES PUDDEFOOT, a citizen of the United States, residing at Detroit, in the county of Wayne and State of Michigan, have invented and produced a certain new, original, and ornamental Design for a Stove, of which the following is a specification, reference being had therein to the accompanying drawing, in which the figure is

10 a perspective view of the stove.

A designates the stove-base, having the supporting-legs B, and C is the stove-body, substantially elliptical in form, mounted upon the base. As shown, the body is provided 15 with a series of vertically-projecting arched ribs D, extending circumferentially about the body and terminating at their upper and lower ends, respectively, in ornamental annular ribs E and F at the upper and lower edges of the

20 body.

G designates a stove-top similar in form to the contour of the body.

H is an ornamental cover for the fuel-opening in the top, and I the stack.

J designates an ornamental check-damper 25 in the stove-front beneath the top, and K a draft-section in the front of the stove, in the lower portion thereof.

The leading feature of the design resides in the general configuration of the stove and in 30 the surface ornamentation of the stove-body as illustrated.

What I claim as my invention is—

The ornamental design for a stove substantially as herein shown and described. 35

In testimony whereof I affix my signature in presence of two witnesses.

CHARLES PUDDEFOOT.
